UNITED STATES PATENT OFFICE.

ISAAC HARRIS, OF BUFFALO, NEW YORK, ASSIGNOR TO UNITED RADIO CORPORATION,
OF ROCHESTER, NEW YORK, A CORPORATION OF NEW YORK.

DESIGN FOR A CABINET FOR LOUD-SPEAKERS.

Application filed March 9, 1928. Serial No. 25,770. Term of patent 14 years.

To all whom it may concern:

Be it known that I, ISAAC HARRIS, a citizen of the United States, residing at Buffalo, in the county of Erie and State of New York, have invented a new, original, and ornamental Design for Cabinet for Loud-Speakers, of which the following is a specification, reference being had to the accompanying

drawing, forming part thereof, in which the figure is a perspective view of a cabinet for loud speakers according to my invention.

I claim:

The ornamental design for a cabinet for loud speakers substantially as shown.

ISAAC HARRIS.
